UNITED STATES PATENT OFFICE.

WILLIAM LORAN FODREA, OF LITTLE ROCK, ARKANSAS.

ADJUSTABLE SEAT POST.

Application filed August 31, 1920. Serial No. 407,135.

To all whom it may concern:

Be it known that I, WILLIAM L. FODREA, a citizen of the United States, residing at Little Rock, in the county of Pulaski and 5 State of Arkansas, have invented certain new and useful Improvements in Adjustable Seat Posts, of which the following is a specification.

This invention relates to new and useful 10 improvements in seating means and more particularly to the type used in connection with velocipedes and other like machines, the primary object of the invention being to provide seating means so mounted that the 15 angle of inclination thereof may be varied and also to provide means for retaining the seating means in any desired adjusted position.

Another important object of the invention 20 is to provide a device of the above type whereby the seating means may be easily and quickly adjusted to other angles of inclination without necessitating the use of the hands of a cyclist and which may be 25 retained in the desired adjusted position by exerting pressure thereon, the weight of the cyclist upon the seating means serving to exert a pressure thereon.

Another object of the invention is to provide 30 a device of the above nature including means whereby the seating means may be locked in the desired adjusted position.

Still another object of the invention is to 35 provide a device including seating means normally supported out of engagement with the retainer means whereby the former may be readily adjusted without any great effort upon the part of the cyclist, the means for supporting the seating means in this position being of a nature whereby the seating 40 means may be readily engaged with the retainer means when the weight of the cyclist is imposed on the seating means.

Other object and advantages of the invention 45 will become apparent during the course of the following description.

In the accompanying drawings forming a part of the application and wherein like numerals are employed to designate like 50 parts throughout the several views—

Figure 1 is a side elevation of a portion of a velocipede frame.

Figure 2 is a top plan of the same.

Figure 3 is an enlarged fragmentary view

of the means for retaining the seating means 55 in various adjusted positions.

Figure 4 is a vertical section taken on the line 4—4 of Figure 3.

Figure 5 is a transverse section of said means taken on the line 5—5 of Figure 3. 60

Figure 6 is a side elevation of a conventional bicycle frame having the invention applied thereto.

Figure 7 is a top plan of the frame, parts 65 thereof being broken away.

Figure 8 is a fragmentary longitudinal section of the retaining means, and

Figure 9 is a transverse section of the same on the line 9—9 of Figure 8.

Referring to the drawings wherein for the 70 purpose of illustration is shown the preferred embodiment of the invention I have illustrated the use of the invention in connection with bicycles but it is of course understood that I do not care to restrict the 75 use of the invention to velocipedes and other like machines as the same may be used equally as well in other connections. In Figures 1 to 5 inclusive I have illustrated the invention as applied to a bicycle frame 80 especially constructed for use in embodying the invention therein, while in Figures 6 to 9 inclusive I have shown the invention applied to a bicycle frame of the latest conventional type. In both instances, the frames 85 consist of a pair of horizontal bars 10 and 11 which are connected to front and rear struts 12 and 13 respectively, the rear struts 13 in the form illustrated in Figures 6 to 9 inclusive being the one in which the ordinary saddle post is mounted. The usual rear 90 forks 14 have been illustrated in this instance, in view of the fact that the front forks do not co-operate with the present invention.

In the form of the invention illustrated in 95 Figs. 1 to 5, the seating means consists of a post 15 which is made up of a pair of telescopic members, one of which assumes the form of a rod 16 having its lower end 17 enlarged and bifurcated whereby the same 100 may straddle and be pivotally connected to the front strut 12 as at 18. A coiled spring 19 of the compression type surrounds the rod 16, with one end of the spring abutting with the enlarged end of the rod, while the opposite end of the coiled spring abuts with the lower end of the coacting telescopic member indicated by the numeral 20. The telescopic

members are prevented from relative turning movement by the provision of a pin 21 secured to the rod 16 and operating in an elongated longitudinally extending slot 22 in the member 20.

The means provided for normally urging the post 15 forwardly of the frame consists of a rod 23 connected to the enlargement 17 of the telescopic member 16 and adapted to operate through an opening provided in the lower end of the rear strut 13. A coiled compression spring 24 surrounds this rod and bears against the strut 13 and the enlargement 17.

15 The upper end of the seat post 15 extends upwardly through the slotted rear ends 25 and 26 of the two horizontal bars 10 and 11 respectively. This rear slotted portion 25 of the upper horizontal bar constitutes 20 retainer means and the portion of this bar forming the sides of the slot are in the form of channel irons 27, each of which is equipped at its top and bottom with inwardly extending flanges 28. As most 25 clearly seen in Figures 2, 3 and 5, the upper flanges 28 are provided with oppositely disposed notches 29 spaced longitudinally along the flanges.

The upper end of the seat post is provided 30 with an enlarged hollow head 30 which operates in the rear slotted portion of the horizontal bar 10. This head has its opposite sides provided with outwardly projecting ribs 31, the lower ends of the same terminating above the top of the slotted portion 25 of the horizontal bar 10 when the tubular section 20 of the seat post 15 is arranged in its uppermost position. Consequently, it will be seen that the seat post may 40 be swung longitudinally of the frame to vary its angle of inclination and when it is desired to adjust the post in any certain position, pressure upon the head 30 is exerted to cause downward movement thereof where- 45 by the ribs 31 carried by the same will be caused to enter a pair of the oppositely disposed notches to preclude swinging movement of the post 15 upon its pivot 18.

In order that the post may be locked in 50 the desired adjusted position, a catch 32 is pivoted within the head 30 to depend therefrom, the lower arcuate end 33 having a knob thereon disposed exteriorly of the head. The catch is provided with a laterally pro- 55 jecting finger 34 which extends through an opening in the head 30 when the catch is swung into an operative position. When the finger 34 of the catch is projected through the opening and the seat member is forced 60 upwardly, it will be seen that the finger will be engaged with one of the lower flanges 28 provided upon the portion 27 constituting sides of the slot in the horizontal bar 10.

Consequently upward movement of the tubu- 65 lar member 20 of the post is prohibited.

In order that a bicycle saddle of the well known type may be associated with the seat-post, the upper end of the post 15 is extended within the head 30, the upper end of which is provided with an opening whereby the 70 end of a saddle post 36 may be inserted therethrough and into the upper end of the post 15. The rear portion of the head 30 is split and is provided with a pair of resilient extensions 37 the sections of which 75 are clamped about the saddle post by rivets or bolts 38.

The form of invention illustrated in Figures 6, 7, 8, and 9 operates under the same principle as the form heretofore disclosed, and embodies a post 15' consisting of upper and lower telescopic members 16' and 20' the lower member 16' operating within the upper member and having its lower end pivotally connected to a bracket 17' fastened to the lower end of the post strut 13. The upper end of the telescopic member 20' is equipped with a pair of spaced arms 39 which are adapted to straddle and be arranged upon opposite sides of horizontal bars 10 and 11. Slots 40 are provided in the front and rear faces of the telescopic member 20' whereby a pin 41 which is loosely mounted within the telescopic member 16' may operate therein. One end of the pin 41 is disposed at right angles to the pin as indicated at 42 and is adapted to operate in and co-operate with the slot in the manner to provide locking means for retaining the seat post 15' in any desired adjusted position. The opposite end of the pin 41 is provided with an eyelet into which is fastened one end of a coiled spring 43, which by its connection with a clip 44 fastened to the forward strut 12 tends to normally retain the 105 post 15' in a forwardmost position and the angular end of pin 41 against the member 20''. This arrangement of the angular end of the pin will be normally maintained by the spring 19 normally urging the seat post 15' upwardly so that the lower ends of the slots 40 will be urged into engagement with the pin 41. Consequently, when downward pressure is exerted on the seat post 15', the slots 40 are moved downwardly with respect 115 to the pin 41 and since the spring 43 normally pulls the pin 41 forwardly, the angular end 42 of this pin will spring into the rear slot 40 when the latter are moved far enough down upon the telescopic member 120 16' to permit the angular end 42 of the pin to enter the slot and abut the end thereof so as to prevent the spring 19 moving the seat post 15' upwardly. Therefore, it will be obvious that the projection 51 will be reasonably retained in engagement with one of the openings in the retainer bar. 125

The retainer means in the present type of invention consists of an arcuate bar 45 secured to the frame of the bicycle by having 130

one end fastened to the horizontal bar by a suitable clip 46 as clearly shown. The rear end of the retainer bar is provided with a depending leg 47 which is adapted to be secured within the upper portion of the tubular post 13. The bar 45 is equipped with a plurality of longitudinally spaced openings and the longitudinal edges of the bar are bent downwardly to provide a pair of depending flanges 49.

The arms 39 of the seat post are arcuated rearwardly as clearly seen in Figure 6 to straddle and be arranged in proximity to the retainer bar 45. To the free ends of these arms 39 is secured a head 50 which consists of a roof portion 51 and a pair of depending side walls 52 which are adapted to engage the side flanges 49 of the retainer bar for guiding the seat post. A saddle post 53 rises from the head 50 for the purpose of having secured thereto a saddle of any desired type. The under side of the roof 51 is equipped with depending lug or leg 54 adapted for co-operation with any of the spaced openings 48 in the retainer bar. As clearly seen in Figure 8, the spring 19' which bears against the lower end of the telescopic member 20' of the seat post 15' urges the post to a position whereby the lug 54 is disengaged from the retainer bar whereby the cyclist may readily vary the adjustment of the seat post. However, when it is desired to retain the seat post in an adjusted position, the cyclist manipulates the same to move it forwardly or rearwardly of the bicycle to the desired point. When one imposes his weight upon the saddle, the telescopic member 20', of the seat post compresses the spring 16', whereupon the leg 54 carried by the head 50 passes through one of the openings 58 in the retainer bar 45. When it is desired to lock the seat post in the desired adjusted position, the angular end 42 of the pin 41 is turned downwardly so that it will be drawn into the slot 40 so that its free end engages the closed end of the slot 40 to prohibit upward movement of the telescopic member 15'. However, when it is desired to make a new adjustment of the seat post, the angular end 42 of the pin is moved upwardly whereupon the upper member 15' of the seat post springs upwardly under the force of the spring 16' to disengage the lug 54 from its opening. After the weight of the cyclist has been removed from the post, it immediately springs forwardly to the forward end of the retainer bar under the influence of the spring 43 and this movement is limited by the arms 39 striking the clamp 46. Rearward movement of the seat post is limited by the lug 54 engaging an upturned lip 55 provided upon the rear end of the retainer bar 45.

From the foregoing description it will be apparent that this invention renders the pro-

pelling of bicycles comparatively easy, inasmuch as the cyclist may position himself relative to the bicycle frame whereby the maximum amount of force may be exerted against the pedals when the seat post is arranged in substantially a perpendicular position. In coasting down hills the cyclist may relax by swinging the post rearwardly of the bicycle so as to incline the seat post.

The foregoing description and the accompanying drawings have reference to the preferred embodiment of my invention. It is to be understood however, that such changes may be made in construction and arrangement of parts, materials, dimensions, etc., as may prove expedient and fall within the scope of the appended claims.

I claim—

1. Seating means movable to vary the angle of inclination thereof, retainer means adapted for co-operation with the seating means and adapted to retain the latter in various adjusted inclined positions, and means for resiliently supporting the seating means to permit relative movement between the seating means and the retainer means, and being operable by pressure applied thereto to permit engagement of the seating means with the retainer means for the purpose set forth.

2. Seating means movable vertically and in a direction to vary the angle of inclination thereof, retainer means associated with said seating means, means for normally retaining said seating means disengaged from the retainer means, and means carried by the seating means and engageable with the retainer means to prevent relative movement between the seating means and the retainer means.

3. Seating means comprising a spring supported pivoted seat post, retainer means associated therewith, a seat carried by the post, said post being movable vertically relative to the retainer means whereby the post may be engaged with the retainer means when pressure is applied to the post to force it into cooperative engagement with the retainer means.

4. Seating means comprising a pivoted seat post, retainer means associated with said post and having interlocking means disposed at spaced intervals throughout its length, said seat post being movable vertically of the retainer means, and said seat post having a projection adapted for co-operation with the interlocking means when pressure is applied to said post.

5. Seating means comprising a pivoted seat post, retainer means cooperating therewith and having a plurality of spaced notches throughout its length, said seating means being movable vertically of the retainer means and equipped with an extension adapted to be brought into cooperative

engagement with one of the notches when weight is imposed upon the seat post.

6. Seating means comprising a seat post pivotally mounted, retainer means associated therewith and equipped with a slot, the edges of which are notched, said seat post having a head carried thereby and adapted to ride in the slot of the retainer means when the inclination of the post is varied, said head being provided with a lateral extension normally disposed above the retainer means and adapted to be brought into cooperative engagement with one of the notches when weight is imposed upon the head.

7. Seating means comprising a pivoted seat post, retainer means comprising a slotted member having notches associated therewith, a head carried by said seat post and disposed in the slot of the retainer means, said head being movable vertically of the retainer means and provided with a lateral extension adapted for cooperation with the notches of the retainer means, and latch

means carried by the head and adapted for cooperation with the retainer means to retain the head in a lowered position whereby its extension will be retained in engagement with one of said notches.

8. The combination with a velocipede frame including a plurality of struts and a seat post pivotally mounted upon one of the struts, a seat mounted upon the post, a rod pivotally connected to the post and slidably mounted through another of the velocipede struts, a spring positioned upon said rod to normally urge the post forwardly of the frame, and means carried by the post for retaining the same in various adjusted positions with respect to the frame.

In testimony whereof I affix my signature in presence of two witnesses.

WILLIAM LORAN FODREA.
